TELEGRAPH TRANSMITTING SYSTEM

Kimmel A. Sylvester, Skokie, Ill., assignor to Tele-type Corporation, Chicago, Ill., a corporation of Delaware

Application April 18, 1941, Serial No. 389,146.

10 Claims. (Cl. 178—3)

The present invention relates to printing telegraph systems, and more particularly to control systems therefor.

The principal object of the invention is the provision of a selector system to control transmission from a group of transmitters to a single channel of communication.

Another object is to provide an electrical relay selector system for controlling the automatic and sequential transmission of messages from a plurality of tape transmitters to a single channel of communication in accordance with the sequence of tape placement in the transmitters.

A further object of the invention is to provide a cam disc type of selector for facilitating automatic and sequential transmission of messages from a plurality of tape transmitters to a single channel of communication in accordance with the sequence in which the tape is inserted in the transmitting units.

In commercial telegraph offices, the handling of messages is facilitated by providing a selector system and apparatus which will permit sequential automatic transmission of messages to a single outgoing channel of communication from individual transmitting units of a number of groups or banks of units distributed about the office. That is, one or more units of each group of units may be connected to the same outgoing line, and the selector system according to the present invention controls the sequence in which the transmission from these units takes place. The individual units may be connected either directly to the outgoing line, or to a reperforator located adjacent to a transmitter common to all units and connected to an outgoing line. The individual transmitter unit identified with a particular channel of communication may or may not be in the same bank.

A complete understanding of the foregoing and other objects of the present invention may be had from the following description when taken in conjunction with the accompanying drawings, in which

Fig. 1 is a diagram illustrating the connections whereby sequential control of transmission from an uneven distribution of transmitting distributors per channel may be effected;

Fig. 2 is a diagram illustrating the connections whereby sequential control of transmission from an even distribution of transmitting distributors per channel may be effected;

Fig. 3 is an electrical relay selector system for providing automatic and sequential transmission of messages, from a plurality of transmitting

distributors to a single channel, in accordance with the sequence of tape placement in the transmitters;

Fig. 4 is a plan view, partly in section, of a cam disc type of selector for controlling automatically the sequential transmission of messages to a single channel in accordance with the order of placement of the tape in the transmitters;

Fig. 5 is an elevational view, partly in section, of the cam disc type of selector shown in Fig. 4;

Fig. 6 is a sectional view taken at line 6—6 of the Fig. 5;

Fig. 7 is a sectional view taken on line 7—7 of Fig. 5;

Fig. 8 is a schematic arrangement of the essential elements of the cam disc type of selector of the present invention; and

Fig. 9 is a plan view of a bank of transmitters showing the association of the cam disc type of selector therewith.

Having reference to Figs. 1, 2, and 3, the banks of transmitting units are indicated by the numerals 11, 12, 13, and 14 and are of the type disclosed in copending application Serial No. 345,456 filed July 15, 1940 by M. T. Goetz, now Patent No. 2,296,845, granted Sept. 29, 1942. Each of the units 11 to 14 comprises a plurality of tape transmitter distributors 15, and if it is desired to transmit from various ones of the units 15 to the same signal line or channel, the units 15 are connected through banks of relays 16, 17, 18, or 19 (Fig. 1) to signal channels 26, 27, 28, or 29, or banks of relays 21, 22, 23, and 24 (Fig. 2) to channels 31, 32, 33, and 34, respectively. In the particular arrangement shown in Fig. 1, the tape transmitting units 15 identified with XD—1, XD—4, and XD—6 of the bank or multiple unit 11; XD—1 and XD—4 of the multiple unit 12; XD—1 of multiple unit 13, and XD—1 of multiple unit 14 are connected through relay bank 16 to the single channel 26. Likewise, XD—2 of multiple unit 11, XD—2 and XD—6 of multiple unit 12; XD—2 and XD—5 of multiple unit 13, and XD—2 of unit 14 are all connected through the relay bank 17 to the channel 27. Similarly, it can be noted from Fig. 1 the particular transmitting distributor units 15 which are connected through their respective relay banks 18 and 19 to the channels 28 and 29. The same can be seen from Fig. 2 wherein one transmitting unit from each multiple unit is connected through a relay bank 21 to 24 to the respective channels 31 to 34.

For purposes of illustration, there is shown in Fig. 3 a relay bank serving four transmitting distributor units 15, one in each bank of units 11 to

14. As disclosed in the aforementioned copending application, each of the transmitter distributor units 15 includes a tape-out contact 35 and a clutch trip magnet 36. In the arrangement according to the present invention, the number of relays in a relay bank, such as shown in Fig. 3, is the square of the number of transmitting distributor units 15 controlled. In Fig. 3, four units 15 are controlled, hence the relay bank comprises sixteen relays. In the arrangement shown in Fig. 3, each of the transmitter units 15 is provided with a group of four relays. Namely, unit 15 of the bank 11 is provided with a group of relays 41, 42, 43, and 44. Unit 15 of bank 12 is provided with a group of relays 51, 52, 53, and 54. Unit 15 of bank 13 is provided with a group of relays 61, 62, 63, and 64; and unit 15 of bank 14 is provided with a group of relays 71, 72, 73, and 74.

Upon inserting tape in the unit 15 of bank 11, the tape-out contact 35 is closed and a circuit is completed from battery 70, over conductor 75, conductor 76, through contact 35, over conductor 77, through contact 78, over conductor 79, through contact 81, over conductor 82, through contact 83, over conductor 84, through contact 85, over conductor 86, through the winding of relay 41, thence through its contact 87, over conductor 88, through contact 89 of relay 71, over conductor 91, through contact 92 of relay 61, over conductor 93, through contact 94 of relay 51, over conductor 95, and through contact 96 of relay 41 to ground. Upon the completion of this circuit, relay 41 will become energized, and its four make-before-break contacts will be operated to open the contacts 87, 96, and 85 and close its contacts 97, 98, 99, and 101. The closing of contact 97 applies ground to a locking circuit for relay 41, from ground, through contact 97, then through the winding of relay 41, over conductor 86, through contact 99, over conductor 65, and then through contact 66 of relay 42 to positive battery. Contact 101 is closed when relay 41 is energized, so that the energizing circuit for relay 42 is completed before the locking circuit for relay 41 is broken. The energizing circuit for relay 42 extends over that portion of the previously described energizing circuit for relay 41 up to conductor 84, thence the circuit continues through contact 101, through the winding of relay 42, then through contact 102 of relay 42, over conductor 103, through contact 104 of relay 72, over conductor 105, through contact 106 of relay 62, over conductor 107, through contact 108 of relay 52, over conductor 109, thence through contact 111 of relay 42 to ground. Upon energization, relay 42 pulls up its make-before-break contacts to open contacts 102, 111, 66 and 83, and close contacts 112, 113, 114, 115, and 116. The opening of contact 66 will break the locking circuit for relay 41. The closing of contact 112 applies ground to a locking circuit for relay 42 (which ground was applied before the opening of contact 102) from ground through contact 112, through winding of relay 42, over conductor 67, through contact 115, over conductor 68, then through contact 69, to battery. Simultaneously, contact 116 is closed before contact 83 is opened to complete an energizing circuit for relay 43 before relay 42 is de-energized. The energizing circuit for relay 43 extends from that portion of the first-mentioned energizing circuit for relay 41 up to conductor 82, then through contact 116, through the winding of relay 43, through its contact 117, over conductor 118, through contact 119

of relay 73, over conductor 121, through contact 122 of relay 63, over conductor 123, through contact 124 of relay 53, over conductor 125, thence through contact 126 of relay 43 to ground.

5 The energization of relay 43 will cause its make-before-break contacts to be operated to close contacts 127, 128, 129, 131, and 132. The closing of contact 127 applies ground to complete a locking circuit for relay 43 from ground through contact 127, through winding of relay 43, over conductor 110, through contact 131, over conductor 120 and through contact 89 to positive battery. However, the energizing circuit for relay 43 will be broken upon the opening of contact 81 which opens following the closure of contact 132. The opening of contact 81 and the closing of contact 132 causes an energizing circuit to be completed for relay 44 over that portion of the first-described energizing circuit for relay 41 up to the conductor 79, then through contact 132, through the winding of relay 44, through contact 133, over conductor 134, through contact 135 of relay 74, over conductor 136, through contact 137 of relay 64, over conductor 138, through contact 139 of relay 54, over conductor 141, thence through contact 142 to ground. Upon the energization of relay 44, its make-before-break contacts will be operated to close contacts 143, 144, 145, 146, and 147, and to open contacts 133, 142, 78, and 80. The opening of contact 80 removes locking battery from relay 43 allowing it to restore to its unoperated position. The circuit for relay 44, being broken at contact 78, will be established through contact 146 over conductor 148, through the winding of relay 44, thence through contact 143 to ground. The energization of relay 44, by operating the contact 147 thereof, completes a circuit for the clutch trip magnet 36 of unit 15 of bank 11 from battery, through contacts 147, over conductor 149, through the winding of clutch trip relay 36 of the transmitter distributing unit 15, thence over conductor 151 to ground. The operation of the clutch trip magnet 36 permits the transmitting cam shaft of said unit 15 to be rotated continuously to step the tape along and to transmit the signals over the line wire 152.

While transmission is taking place from multiple unit 11, tape may be inserted in any of the other multiple units 12, 13, or 14. Assuming that tape is now inserted in a unit 15 of bank 12, as indicated in the Figure 3, a circuit is completed from battery 70, over conductor 75, through tape-out contact 153 over conductor 154, through contact 155, over conductor 156, through contact 157, over conductor 158, through contact 159, over conductor 161, through contact 162, over conductor 163, through the winding of relay 51, through contact 164, over conductor 88, through contact 89, over conductor 91, through contact 92, over conductor 93, through contact 94, over conductor 95 and through contact 96 of relay 41 to ground. Upon energization, relay 51 pulls up its make-before-break contacts 166, 167, 168, and 169. Closure of contact 166 completes a locking circuit to relay 51 from ground, through contact 166, through winding of relay 51, over conductor 163, through contact 168, over conductor 139, and through contact 140 to battery. Closure of contact 169 completes an energizing circuit for relay 52 over that portion of the previously described energizing circuit for relay 51 up to conductor 161, thence through contact 169 and through the winding of relay 52, through contact 171 thereof, then over conductor 103, through contact 104 of

relay 72, thence over conductor 105, through contact 106, over conductor 107, through contact 108, over conductor 109, and through contact 111 of relay 42 to ground. An energizing circuit is completed for relay 52 over this circuit which causes its make-before-break contacts to be operated, and in a manner similar to the action of the circuits hereinbefore described, the contact 159 of relay 52 will be opened and its companion contact 173 will be closed to complete an energizing circuit for relay 53 over a portion of the previously described energizing circuit for relays 51 and 52.

The operation of the contacts associated with relay 53 will not cause the energization of relay 54 at this time as was the case in the series of relays 41 to 44, because tape is being stepped by the unit 15 of bank 11 and signals are being transmitted over the line 152 therefrom, and during this transmission, relay 54 cannot be energized upon the closure of contact 174 associated with contact 157 of relay 53 because of the fact that the ground for the energizing circuit for relay 54 is cut off by the opening of contact 142 of relay 44. However, when the tape has become depleted from the unit 15 of bank 11 and the tape-out contact 35 has become opened, the energizing circuit from battery 70 over the aforescribed circuit to relay 44 will be broken and hence relay 44 will become de-energized, thereby opening its contacts 143 to 147, inclusive, and closing its contact 142, thereby applying ground to the previously prepared circuit for relay 54 which will become energized and pull up its make-before-break contacts and close its contacts 175, 176, 177, 178, and 179. The closure of contact 179 of relay 54 completes an energizing circuit for the clutch release or trip magnet 181 of the unit 15 of bank 12 from battery, through contact 179, over conductor 182, thence through the winding of magnet 181 and over the conductor 151 to ground. The energization of the clutch magnet 181 causes the transmitting cam distributor to be operated continuously, and the tape to be stepped ahead constantly to effect the transmission of signals over the line wire 152 from the operated unit in the bank 12.

It will be understood from the foregoing description that when tape is inserted in a transmitting distributor 15, the relays 41 to 44, 51 to 54, 61 to 64, and 71 to 74, in the bank of relays associated therewith will operate in succession from left to right, for example, relay 41 releasing after relay 42 pulls up; relay 42 releasing after relay 43 operates; and relay 43 releasing after relay 44 operates. Relay 44 remains locked in the operated position through the tape-out contact 35 located in the transmitting distributor 15 of bank 11, and the contact 146 of relay 44 until the tape in the transmitting distributor has been stepped out and the tape-out contact 25 opens. When relays 44, 54, 64, or 74 of any group of relays of which they form a part is in the operated position, transmission from the corresponding transmitting distributor occurs by means of the corresponding transmitter distributor stop magnet 36 being energized through their contacts 147, 179, 183, or 184.

As was also described, when the tape was inserted in a unit 15 of the second group of units 12 while tape remained in a unit 15 of the first group of units 11, the relays 51 to 54 in the second group of relays operated from left to right in the manner just described, except that the stepping process stopped at relay 53. Relay 53

remains locked up in an operated position through contact 180 of relay 54 of its own group of relays, its own contacts 165 and 172 being closed. Relay 54 cannot operate until relay 44 of the previous transmitter group has released, that is, transmission from the transmitting distributor in bank 12 does not begin until relay 54 operates.

If tape is inserted in a transmitter unit 15 of either of the remaining groups of relays 61 to 64, or 71 to 74, while tape still remains in the previous two groups of relays, the relays 61 to 64 or 71 to 74 will operate in succession from left to right. Assuming that tape is inserted first in bank 13 and then in bank 14, the stepping process will terminate at relay 62 of the group 61 to 64, and relay 71 of the group 71 to 74. Relay 62 of the group 61 to 64 will be locked up through contact 185 of relay 63, its own contacts 186 and 187 being closed. Relay 71 will remain locked up by a circuit extending through contact 183 of relay 72 and its own contacts 189 and 191.

When tape runs out of the transmitting distributor 15 of bank 11 in which tape was first placed, its tape-out contact 35 opens, as previously mentioned, removing battery from relay 44 of the group of relays 41 to 44, through contact 146. As relay 44 releases, closure of contact 142 makes available a common ground return for relays 54, 64, and 74 of the other groups of relays. The next transmitting distributor in which tape was placed, namely, distributor unit 15 of bank 12, has its relay 53 locked in the operating position and has had battery for relay 54 in readiness through a circuit including its contact 174 and tape-out contact 153. This circuit is now completed upon closure of contact 142 of relay 44, and relay 54 is energized and is locked in its operating position through the tape-out contact 153, and its own contacts 176 and 175. Transmission now takes place from the transmitting unit 15 of bank 12. As relay 54 operates, relay 53 of the same group releases and closure of its contact 139 makes available a common ground return circuit for relays 43, 63, and 73 of the other groups. The group of relays, namely, 61 to 64, in which the stepping process has stopped at relay 62 now steps up to relay 63. Likewise, the group of relays, namely, 71 to 74, in which the stepping process has stopped at relay 71 now steps up to 72. The energizing circuit for relay 41 of the first group of relays energized, namely, 41 to 44, is now ready for another signal from the tape-out contact 35 of its associated unit 15. However, at this particular time, the only transmitting distributor 15 in which tape may be placed is the one which has just completed the transmission of its tape.

Although the foregoing description was directed to the preparation for transmission of the units in the successive order from bank 11 to bank 14, the circuit arrangement provides for the preparation of the groups of relays in any order, and transmission from the various units will take place in the order or sequence of the placement of the tape in the respective transmitting unit. For example, if it be assumed that the unit 15 of bank 11 is transmitting over the line 152, and tape is first inserted in the unit 15 of bank 13 during such transmission instead of at bank 12, as previously described, grounded battery at 79 will be connected over the tape-out contact of unit 15 of bank 13 to energize the chain of relays associated therewith. The relays associated with this unit will be sequentially momentarily energized, as described hereinbefore in connection

with another series, and relays 61 and 62 will be de-energized and relay 63 will be held energized from battery at break contact 45 of relay 64. Since the ground connection for completing the energizing circuit of relay 64 is broken at contact 142 of relay 44 until tape at bank 11 is exhausted, the relays of the chain associated with bank 13 will be held in the just described condition until tape at said unit 15 of bank 11 is exhausted; at which time relay 63 will be de-energized, and relay 64 is energized to close contact 183 to establish an energizing circuit for clutch trip magnet 46 of the unit 15 of bank 13.

If it be further assumed that tape was sequentially inserted in the units 11, 13, 12, and 14, relays 44, 53, 52, and 71 will be held energized until tape is exhausted from unit 15 of bank 11, whereupon bank 13 will start to transmit upon de-energization of relay 44, and energization of relay 64. Relays 63, 52 and 71 become de-energized and relays 53 and 72 become energized. As soon as unit 15 of bank 13 has transmitted until its tape is exhausted, relays 64, 53, and 72 will de-energize and relays 54 and 73 will energize. Transmission will ensue from unit 15 of bank 12 until tape is exhausted therefrom, after which relays 54 and 73 will de-energize, and relay 74 will energize to initiate transmission from bank 16.

Modification

According to another form of the invention, a mechanical means of controlling the sequence of transmission in accordance with the placement of the tape in the transmitter is shown in Figs. 4 to 9, inclusive. Mounted on a base plate 201 are a pair of supports 202 and 203 in which is journaled a shaft 204, restrained against edge-wise or axial movement by collars 205 and 206 secured to said shaft. Also mounted on base plate 201 are a pair of spaced side plates 207 and 208. Shaft 204 carries thereon for rotation therewith a plurality of cams 209 to 212, suitably positioned and spaced between plates 207 and 208. Cams 209 to 212 are frictionally connected to shaft 204 by a friction clutch mechanism which comprises a flanged collar 213 secured to said shaft and a flanged collar 214 slidably mounted on said shaft through the instrumentality of key means 215. Friction discs 216 are juxtaposed to the cams 209 to 212 and suitable collars 217 are employed as spacers between said cams. Positioned between flanged collar 214 and support 203 is a collar 218 which is fixed to said shaft, and compressed between collar 218 and the flange of collar 214 is a compression spring 219, by means of which compressive force is applied to the friction members 216 associated with the cams 209 to 212 to permit said cams to rotate with shaft 204 when released for rotation, as hereinafter described. Fixed to shaft 204 between support 202 and plate 207 is a cam member 221, which operates to close a series of contacts 222, 223, 224 and 225 arranged around its periphery as shown in Fig. 7. Contacts 222 to 225 are appropriately mounted to the side plate 207 by individual brackets 226 (Fig. 4). Contacts 222 to 225 are normally held open under their own spring tension, and cam 221 upon rotation with shaft 204 acts upon the extended arm 227 of each of said contacts to close them successively.

Spanned between plates 207 and 208 is a bracket 229 for supporting a plurality of magnets 231 to 234 (Fig. 4). Magnets 231 to 234 are individual to cams 209 to 212, respectively, and

control magnetically a series of pawl members 235 associated with each of the cams 209 to 212. Pawls 235 are pivotally mounted on a shaft 236 journaled in side plates 207 and 208. Pawls 235 are normally biased in a clockwise direction (as viewed in Figs. 6 and 7) by individual springs 230. Each of the pawls 235 is provided with a pair of pallets 237 and 238. Each lever 235 is also provided with an extension 239 (Fig. 6) which cooperates with spring 241 of a pair of contacts 242. Contacts 242, of which there is one pair associated with each cam 209 to 212, carried on a bracket 243 supported on the base plate 201. Cooperatively associated with each cam 209 to 212 is a contact 244 (Fig. 7) mounted on a bracket 245 extending between the side plates 207 and 208. Positioned between side plates 207 and 208 and appropriately arranged adjacent to the peripheries of cams 209 to 212 are a plurality of inverted trough-like members 247 which are rockably supported on pilot screws 246 in the side plates 207 and 208. Each of the members 247 is provided at one end thereof with an extension 248, to the extremity of which is secured one end of a spring 249, the other end of which is secured to a spring post 251 mounted in the side plate 208. In this manner each of the members 247 is biased in a clockwise direction (as viewed in Fig. 6) and is held against the spring post 251 of its adjacent member, acting as a stop. The cams 209 to 212 are shown in Fig. 6 in an intermediate position with the projection 252 of cam 209 approaching the pallet 238, whereat it will be arrested while the escapement lever 235 is in its released or clockwise position. The flange 253 of the members 247 is of such height that, when the members 247 are biased in their clockwise position against stops 251, the cam portions 252 of the cams 209 to 212 will be permitted to pass thereunder. The flanges 254 of members 247 are inclined, as shown, so that as the cam portions 252 pass thereunder, the members 247 will be rocked counterclockwise about their pilot screws 246 against the tension of the springs 249, thus permitting the cam portions 252 to continue their movement in transit.

Assuming that all of the cams 209 to 212 have been rotated in a clockwise direction (Figs. 6 and 7) through their frictional connection with shaft 204 to bring all of the cam projections 252 in contact with pallets 238 of their respective escapement levers 235, and assuming further that magnet 232 associated with cam 209 has become energized (in a manner to be presently described) the escapement lever 235 will be moved magnetically in a counterclockwise direction against the action of spring 230, from the dotted line position shown in Fig. 7 to the full line position, thus releasing cam 209 for rotation. Cam 209 will rotate until its cam portion 252 engages pallet 237, as shown in Fig. 7. In this position, cam portion 252 will hold contact 244 closed. While the cam projection rests against pallet 237 and holds the member 247 in its counterclockwise position through the co-action of flange 254 and cam portion 252, the flange 253 is presented in the path of the cam portion 252 of each of the remaining cams 210 to 212, so that when any of the remaining magnets 231 becomes energized to release its associated cam 210 to 212 for rotation, said released cam will rotate until its cam portion 252 strikes against the flange 253 of the previously operated member 247. The cam portion 252 of the next operated cam 210 to 212 was permitted to pass underneath the flange 253 of the member

247 next adjacent (in a counterclockwise direction) to the first operated member 247 because said member 247 was held in its clockwise position against stop 251 by its spring 249. However, after the next operated cam 210 to 212 has been rotated until its cam portion 252 strikes flange 253 of the first operated member 247, the member 247 adjacent to the first operated member 247 will also assume its counterclockwise position with the flange 254 resting upon the apex of the cam portion 252, and holding its flange 253 into the path of the remaining cam portions 252.

As the magnet 231 remains energized it holds its escapement pawl 235 in the attracted position, and the projection 239 thereon holds contact 242 closed. Also contact 244, as previously indicated, remains closed, the purpose of which will presently appear. As previously described, cam 221 constantly rotates to close contacts 222 to 225, successively, the purpose of which will also appear in the ensuing description of operation.

General operation

The unit disclosed in detail in Figs. 4 to 7 is indicated by the numeral 255 in Fig. 9 and is shown as directly associated with a bank 256 of transmitting distributor units 15, the shaft 204 being common to both the mechanism 255 and 256.

As set forth in the aforementioned copending application, each unit 15 is provided with a transmitting cam cylinder 257 (Fig. 8) carried on shaft 204 and operatively connected therewith through a suitable clutch mechanism (not shown). For purposes of illustration, the clutch is shown by means of a clutch disc 258 cooperating with a clutch release lever 259 associated with a clutch trip magnet 261. The cam cylinder 257 carries a plurality of contact control cams 262 (only one of which is shown in Fig. 8) which operate through a corresponding plurality of levers 263 to operate their associated contacts. In the particular schematic arrangement shown in Fig. 8, the contact lever 263 is associated with the tape-out pin of the transmitting distributor unit 15 and controls the tape-out contact 264. The tape-out contact 264 is connected on one side to battery 265 and on the other side thereof to a conductor 268, the other end of which is connected to one of the contact springs of the contact 242, the other contact spring of 242 being connected by a conductor 267 to the winding of the magnet 231, thence to ground. The contact 242 is also connected over conductors 263 and 269 to the contacts 222. The remaining contacts 223, 224, and 225 are connected to their respective contacts 242 independently. Contact 244 is connected by means of conductors 271 and 272 to the winding of the clutch trip magnet 261 in the transmitting distributor unit 15.

As set forth in the aforementioned copending application, the insertion of tape in any one of the transmitter distributor units 15 closes the tape-out contact 264 located on that unit. Although only four units 15 are indicated as controlled by the cams shown in Figs. 4 to 7, it is of course understood that the number of cams in the control mechanism shown in Fig. 4 can be increased to serve as many units 15 as desired.

As previously described, the cam 221 rotates constantly and closes contacts 222 to 225 successively, so that at such time when a tape-out contact 264 is closed in the transmitting unit 15 a circuit will be completed, as presently described, for a particular magnet 231 to 234 when its con-

tacts 222 to 225 have been closed by the cam 221. For example, the contact 264 being closed by the insertion of tape, a circuit is prepared from battery through the contact 264 over conductor 266 and conductor 268 to contact 222 which, when closed by cam 221, will complete the circuit through the contact 222 over conductor 269 and conductor 267 through the winding of magnet 231 to ground. This closure of contact 222 being momentary, the operation of magnet 231 will magnetically move the lever 235 counterclockwise to permit the projection 239 to close contact 242, which changes the energizing circuit for magnet 231 from battery 265, through the tape-out contact 264, over the conductor 266, through the contact 242 (now closed), over the conductor 267, and through the winding of magnet 231 to ground. The magnet 231 now remains energized, despite the periodic opening and closing of contact 222, over the afore-described locking circuit. As the magnet 231 has now become energized and the escapement pawl 235 has been rotated counterclockwise, the pallet 238 has been disengaged from the cam portion 252 thereof (see Fig. 7) and the cam 209 will rotate clockwise until its cam portion 252 strikes against the pallet 237 of the same lever 235. The cam portion 252 of cam 209 operates to close contact 244 associated therewith to complete an energizing circuit for the clutch trip magnet 261 of the interconnected transmitting unit 15, from battery 273, through the winding of magnet 261, over conductor 271, through contact 244 and over conductor 272 back to battery 273. The energization of magnet 261 magnetically moves lever 259 out of engagement with clutch member 258 to permit the rotation of the cam disc 257 to initiate transmission of messages under tape control from said interconnected transmitting unit 15.

Now, should tape be inserted in another transmitting unit 15 while the transmission is continuing from the previously operated unit 15, its individual tape-out contact 264 will be closed to cause an energizing circuit for its associated magnet 231 to 234 to be completed so that the cam 210 to 212 associated therewith would be released for rotation. The released cam 210 to 212 would rotate up to the point shown in Fig. 7 represented by the flange 253 of the member 247. It is understood that the cams 209 to 212 may be selected in any order or sequence dependent only upon the sequence of placement of tape in the transmitting units 15. As each cam 209 to 212 is released for rotation, it will rotate until its cam portion 252 is stopped by the flange 253 of the previously operated member 247. After completion of transmission from the unit associated with cam 209, the tape-out contact 264 will be opened and the circuit for magnet 231 will be broken.

The escapement lever 235 associated with the released magnet 231 will be rotated clockwise under the action of its spring 237 to permit the cam 209 to rotate up to the pallet 238 which is now in the cam arresting position. Member 247 (Fig. 7) which was held operated by said cam 209 will be permitted to rotate or rock clockwise by its spring 249 against the stop 251 to remove flange 253 therefrom from blocking relation with the next stopped cam disc 211 or 212 thereby permitting said cam disc to again continue its rotation until it is stopped by the impingement of its cam portion 252 against the pallet 237 of its associated escapement lever 235, whereupon its associated contact 244 will now be closed to

complete a circuit for the trip magnet 261 of the transmitting unit 15 connected thereto to permit transmission from said transmitting unit. Correspondingly, the other cam discs 209, 210, 211, or 212 will move up one position in readiness for transmission after the completion of the transmission from the previously selected unit 15.

Although the present invention has been disclosed in connection with certain specific embodiments thereof, it is understood that such embodiments are merely illustrative and not restrictive, and that all forms coming within the scope of equivalency of the appended claims are intended to be covered by the invention.

What is claimed is:

1. In a telegraph system, a plurality of tape transmitters, a single channel of communication, and means including an electrical relay selector system for facilitating automatic and sequential transmission of messages from said transmitters to said channel of communication in accordance with the sequence of tape placement in said transmitters.

2. In a telegraph system, a plurality of tape transmitters, a single channel of communication, a plurality of cams corresponding to said plurality of transmitters, a source of power tending to rotate said cams, latching devices for normally preventing rotation of said cams, and means effective under control of said transmitters for selectively releasing said latching devices to enable rotation of said cams by said source of power for facilitating automatic and sequential transmission of messages from said transmitters to said channel of communication in accordance with the sequence of tape placement in said transmitters.

3. In a telegraph system, three or more tape transmitters, a transmission channel connectible to said transmitters, and switching means for connecting said transmitters to said channel automatically and sequentially in accordance with the sequence of tape insertion in said transmitters.

4. In a telegraph system, a plurality of tape transmitters, a single channel of communication, means including an electrical relay selector system comprising a group of relays for each transmitter, and circuit means effective automatically to condition the relays in each group for sequential transmission of messages from said transmitters to said channel of communication in accordance with the sequence of tape placement in said transmitters.

5. In a telegraph system, a plurality of tape transmitters, a single channel of communication, and means comprising an electrical relay selector system consisting of a plurality of sequence chains for facilitating automatic and sequential transmission of messages from said transmitters to said channels of communication in accordance with the sequence of tape placement in said transmitters, in which the relays vary in number directly as the square of the number of trans-

mitters, whereby said sequence chains are of equal extent electrically for each tape transmitter.

6. In a telegraph system, a plurality of tape transmitters, a transmission channel connectible to said transmitters, and a switching apparatus comprising electromagnetic switching instrumentalities, said instrumentalities varying in number directly as the square of the number of transmitters and arranged in an equal number of vertical and horizontal rows, and means for connecting said instrumentalities to said channel in accordance with the sequence of tape insertion in said transmitters.

15 7. In a telegraph system, a plurality of tape transmitters, a single channel of communication, and control means including a plurality of cams corresponding to said plurality of transmitters, a source of power tending to rotate said cams, electromagnetically controlled latching devices for normally preventing rotation of said cams, means effective under control of said transmitters for selectively releasing said latching devices to enable rotation of said cams by said source of power, and means controlled by said cams for facilitating automatic and sequential transmission of messages from said transmitters to said channel of communication in accordance with the sequence of tape placement in said transmitters.

30 8. In a telegraph system, a plurality of tape transmitters, a single channel of communication, and control means including a plurality of cams corresponding to said plurality of transmitters, a source of power tending to rotate said cams, escapement devices for controlling the rotation of said cams, rockable bail members peripherally arranged around said cams, each of said members adapted to span all of said cams to be controlled thereby, means effective under control of said transmitters for selectively releasing said escapement devices to enable rotation of said cams by said source of power, and means controlled by said cams for facilitating, through the instrumentality of said bail members, automatic and sequential transmission of messages from said transmitters to said channel of communication in accordance with the sequence of tape placement in said transmitters.

45 9. In a telegraph system, a single channel of communication, three or more transmitters, means associated with each transmitter to condition it for transmission, and means effective automatically to connect said transmitters to said channel of communication in the chronological order of readiness of transmitters.

60 10. In a telegraph system, a single channel of communication, three or more tape transmitters, and means effective automatically to connect said tape transmitters to said single channel of communication in the chronological order of tape placement in each transmitter.
